UNITED STATES PATENT OFFICE.

JAN PIETER REIJNHOUT, OF THE HAGUE, NETHERLANDS.

SPARKING PLUG FOR INTERNAL-COMBUSTION ENGINES.

Application filed December 10, 1919. Serial No. 343,791.

To all whom it may concern:

Be it known that I, JAN PIETER REIJNHOUT, a subject of the Queen of The Netherlands, residing at The Hague, Netherlands, 5 have invented certain new and useful Improvements in Sparking Plugs for Internal-Combustion Engines, of which the following is a specification.

It is well-known in the art that the reliability of internal combustion engines with electric ignition mainly depends upon the operation of the sparking plug. This 10 operation, however, may be interfered with by the process of combustion in the cylinder, 15 for owing to the deposition of solid products of combustion on the sparking points the sparking may be altogether prevented. Moreover, the said points, which are always 20 made of non-precious metal such as nickel, or nickel alloys, are subject to rapid deterioration by the action of the very high temperatures availing in the cylinder, and of the acids formed in the cylinder by the 25 combustion of the lubricant.

Now, I have found that the above disadvantages may be completely avoided by using sparking plugs the sparking points 30 of which are provided with a protective cover of precious metal. Exhaustive tests have proved that practically no solid products of combustion are deposited on sparking points made in accordance with my invention and that said points do not burn away, whereby a perfect sparking under

all conditions is ensured, which is especially 35 valuable for air craft motors.

Preferably the precious metal is deposited on the sparking points by galvanic action. I have found that a gold-silver-alloy is very suitable for the purpose, but platinum also 40 gives satisfactory results.

As a matter of course it is not absolutely necessary for the precious metal to be deposited by galvanic action. I may, for instance, provide the sparking points with 45 the required protecting film by immersing them in a bath of molten precious metal (alloy).

The annexed drawing illustrates a longitudinal section of a sparking plug made in 50 accordance with my invention. In this drawing, *a* are the sparking points, and *b* is the protective cover of precious metal thereon.

I would emphasize that the exact construction of the plug is immaterial as far as my invention is concerned, and that my invention is applicable to electric sparking plugs of any type and construction.

What I claim as my invention is: 60
A spark plug for internal combustion motors having points of non-precious metal, each of said points having a protective covering composed of an alloy of gold and silver.

In testimony whereof I affix my signature.

JAN PIETER REIJNHOUT.
